UNITED STATES PATENT OFFICE.

NANCY PATTERSON DUNCAN, OF PITTSBURG, PENNSYLVANIA.

CAR-FENDER.

No. 846,459.

Specification of Letters Patent.

Patented March 12, 1907.

Application filed November 19, 1906. Serial No. 344,034.

To all whom it may concern:

Be it known that I, NANCY PATTERSON DUNCAN, a citizen of the United States of America, residing at Pittsburg, in the county 5 of Allegheny and State of Pennsylvania, have invented certain new and useful Improvements in Car-Fenders, of which the following is a specification, reference being had therein to the accompanying drawing.

10 This invention relates to certain new and useful improvements in car-fenders; and the invention has for its primary object to provide an automatically-operated fender that will prevent persons from being run down and being injured by street-cars.

15 Another object of this invention is to provide a simple and inexpensive fender which will not injure a person contacting with the same.

20 A further object of this invention is to provide a fender applicable to various types of cars, the fender being strong and durable and highly efficient for the purpose intended.

25 With these and other objects in view the invention consists in the novel construction, combination, and arrangement of parts to be hereinafter more fully described and then specifically pointed out in the claims.

30 Referring to the drawings, forming part of this specification, like numerals of reference designate corresponding parts throughout the several views, in which—

35 Figure 1 is an elevation of my improved fender. Fig. 2 is a plan of the same, and Fig. 3 is a front elevation.

40 In the accompanying drawings I have illustrated an end bolster 1 of a car-truck 2, and to this bolster I secure my improved fender. The fender comprises a rectangular base-frame 3, covered with a netting of wire or rope 4. The base-frame 3 is supported by hangers 5, suitably secured to the bolster 1. The side rails 6 of the base-frame 3 have their outer ends connected by curved arms 45 7 to the hangers 5, said arms being provided with buffers 8, of a resilient material, as rubber. Between the arms 7, side rails 6, and hangers 5 are arranged nettings 9, formed of rope or wire.

50 The outer ends of the side rails 6 of the main frame 3 are provided with outwardly-extending rods 10, having eyelets 11 formed at their outer ends. The rods 10 are connected together by an upper cross-bar 12

and a lower cross-bar 14, the object of which 55 will presently appear.

Hinged to the front rail 15 of the main frame 3 is an auxiliary frame 16, said frame extending forwardly between the bars 12 and 14. These bars serve to limit the up- 60 ward-and-downward movement of the auxiliary frame 16. The outer forward edges of the frame 16 are provided with hook-shaped members 17, connected together by a revolvable roller 18, preferably made of a resilient 65 material, as rubber. The hook ends 19 of the members 17 are adapted to normally rest in the eyelets 11 of the rods 10 and support the auxiliary frame 16 in an elevated position.

70 Should a person or object be run down by a street-car equipped with my improved fender, the auxiliary frame 16 is released to prevent the person or object from passing under the main frame 3. This is accomplished 75 through the medium of the members 17. When a person strikes the roller 18, the same is carried rearwardly until the hook ends 19 of the members 17 become disengaged from the eyelets 11. The disengagement of the 80 hook ends 19 from the eyelets 11 is accomplished by the members 17 sliding through sleeves 20, carried by the frame 16. The auxiliary frame 16 is then permitted to drop, together with the members 17 and roller 18, 85 to the position illustrated in dotted lines of Fig. 1 and in this manner prevent the main frame 4 from passing over a person or object. The curved arms 7, together with the nettings 9, form side frames for the main 90 frame 3 and prevent the person or object carried by the main frame from falling from the sides of said frame.

95 From the foregoing it will be observed that I have devised an automatically-actuated fender adapted to drop into an operative position when striking a person or object, the fender being restored to its normal position after the car equipped with the same has stopped and the person or object removed 100 from the fender.

105 My invention particularly resides in the auxiliary frame 16 and the mechanism for temporarily supporting it in an elevated position, said frame and mechanism being applicable to various types of fenders at present used. Such changes in the size, proportion, and minor details of construction as are per-

missible by the appended claims may be resorted to without departing from the spirit and scope of the invention.

What I claim, and desire to secure by Letters Patent, is—

1. In a fender, the combination with a car, of a main frame supported therefrom, side frames carried by said main frame, outwardly-extending rods carried by said main frame, bars connecting said rods, an auxiliary frame hinged to said main frame and extending outwardly between said bars, hook - shaped members slidably mounted upon said auxiliary frame and adapted to temporarily engage said rods, and a resilient roller connecting said members, substantially as described.
2. A car - fender comprising a suitably-supported main fender-frame, auxiliary-fender supporting-rods pivotally connected at their inner ends to the main fender-frame, and provided with eyes at their outer ends, an auxiliary fender hinged at its rear edge to the forward edge of the main fender-frame

and having a sleeve at each end adjacent its forward edge, hook members slidable in said sleeves and normally engaging in the eyes of said supporting-rods, and a roller carried by said hook members.

3. A car-fender comprising a main fender-frame, an auxiliary fender hinged at its rear edge to the forward edge of the main fender-frame, supporting-rods connected at their inner ends to the main fender-frame and provided with eyes at their outer ends, slidable means carried by the auxiliary fender and engaging in said eyes for normally holding the forward edge of the auxiliary fender suspended, the said slidable means extending forwardly in front of the auxiliary fender, and a roller carried by said slidable means, as and for the purpose described.

In testimony whereof I affix my signature in the presence of two witnesses.

NANCY PATTERSON DUNCAN.
